(57) **CLAIM**

The ornamental design for a shoe sole, as shown and described.

DESCRIPTION

FIG. 1 is a perspective view of a shoe sole showing my new design;

FIG. 2 is a bottom plan view thereof;

FIG. 3 illustrates a bottom view of the shoe sole design of FIG. 1;

FIG. 4 illustrates a left side view of the shoe sole design of FIG. 1;

FIG. 5 illustrates a right side view of the shoe sole design of FIG. 1;

FIG. 6 illustrates a front view of the shoe sole design of FIG. 1; and,

FIG. 7 illustrates a back view of the shoe sole design of FIG. 1.

The portion of the top surface which is left unshaded, is not part of the claimed design.
